United States Patent Office

Des. 208,350
Patented Aug. 15, 1967

208,350

PLASTIC RUNNER

Maynard H. Cheris, Highland Park, Ill., assignor, by
mesne assignments, to Tenex Corporation, Elk Grove
Village, Ill., a corporation of Illinois

Filed Sept. 27, 1965, Ser. No. 87,170

Term of patent 14 years

(Cl. D92—4)

FIG. 2

FIG. 3

FIG. 4

FIG. 5

FIG. 1

FIG. 1 is a top plan view of a plastic runner showing my new design, the design is shown broken away to indicate indeterminate length;

FIG. 2 is an enlarged fragmentary plan view thereof;

FIG. 3 is an enlarged cross sectional view taken on the line 4—4 of FIG. 1; and

FIG. 5 is an enlarged cross sectional view taken on the line 5—5 of FIG. 1.

I claim:

The ornamental design for a plastic runner, substantially as shown and described.
